[57] **CLAIM**

The ornamental design for a bottle, as shown and described.

DESCRIPTION

FIG. 1 is a perspective view of a bottle showing our new design;

FIG. 2 is a front view of the bottle depicted in FIG. 1, the opposite side being identical;

FIG. 3 is a side view of the bottle depicted in FIG. 2, representing a partial rotation of the bottle about its vertical center axis from the front view depicted in FIG. 2, the opposite side being identical;

FIG. 4 is a top view of the bottle depicted in FIG. 2;

FIG. 5 is a bottom view of the bottle depicted in FIG. 2;

FIG. 6 is a perspective view of a second embodiment of a bottle as depicted in FIG. 1;

FIG. 7 is a front view of the bottle depicted in FIG. 6, the opposite side being identical;

FIG. 8 is a side view of the bottle depicted in FIG. 7, representing a partial rotation of the bottle about its vertical center axis from the front view depicted in FIG. 7, the opposite side being identical;

FIG. 9 is a top view of the bottle depicted in FIG. 7; and,

FIG. 10 is a bottom view of the bottle depicted in FIG. 7. The broken line environmental showing is for illustrative purposes only and does not form part of the claimed design.
